UNITED STATES PATENT OFFICE.

IRA F. PECK, OF AUBURN, RHODE ISLAND, ASSIGNOR TO WINSOR & JERAULD MANUFACTURING COMPANY, OF PROVIDENCE, RHODE ISLAND, A CORPORATION OF MAINE.

CLOTH-CLAMP FOR TEXTILE MACHINERY.

SPECIFICATION forming part of Letters Patent No. 710,799, dated October 7, 1902.

Application filed February 27, 1902. Serial No. 95,898. (No model.)

To all whom it may concern:

Be it known that I, IRA F. PECK, a citizen of the United States of America, and a resident of Auburn, in the State of Rhode Island, have invented a new and useful Improvement in Cloth-Clamps for Textile Machinery, of which the following is a specification.

This invention relates to cloth clamps or clips of that class known as "automatic" clips; and it consists in certain novel combinations of parts, including spring-pressure devices, hereinafter set forth and claimed. The combination in one and the same clamp of the automatic principle and the spring-pressure principle in various ways is set forth in United States Letters Patent heretofore granted to Robert P. Winsor, No. 604,103, dated May 17, 1898; No. 644,543, dated February 27, 1900, and No. 667,159, dated January 29, 1901. In all the several clamps set forth in said Winsor patents the spring is applied to the movable jaw, as in the spring-clamps formerly in use and, in common with the latter, fails to relieve the clamps from one limitation or difficulty in their adaptation to the different conditions under which they must operate.

The difficulty to which I refer may bestated as follows: In practice the leading end of the cloth as it enters the tentering-machine is sewed by a cross-seam to the preceding piece, and this is repeated for successive pieces, so as to have a steady run of cloth into the machine. Now in each clamp the jaws must fit very accurately and be perfectly parallel. They should fit so close as to be almost light-proof, and either end of the clamp should hold the thinnest tissue-paper. The movable jaw is supported above (or beneath) the cloth-plate in all automatic clamps by an arm or arms, usually two, and the clamp is organized with reference to retaining the movable jaw in effective position; but if a seam, as above referred to, gets into a clamp at either end it is practically certain to spring the arm or arms and cause the two jaws to get out of parallel, which renders the clamp thereafter unfit for nice work. This trouble has been a great source of annoyance to users of automatic clamps.

The leading object of the present invention is to render the clamp yielding at either end, so that it may accommodate itself to a seam at any point without injurious strain.

Another object is to apply the spring or 55 springs to the cloth-plate instead of to the arm or arms, and thus to incorporate the advantages of spring-pressure in a large class of such clamps to which it has not heretofore been applicable—namely, those in which the arm 60 or arms project rigidly from the tenter chain-link or body of the clamp.

Other objects are to provide for the use of a pair of short spiral springs beneath a loosely-hinged cloth-plate as the improved spring device and in this connection to facilitate adjusting the clamp and regulating the spring-pressure as to tension.

Three sheets of drawings accompany this specification as part thereof.

Referring to the drawings, Figure 1 is a sectional plan view of an improved cloth-clamp. Figs. 2 and 3 are end views of the same, the former partly in section, showing the movable jaw and controller in their elevated positions 75 and their lowered or working positions, respectively. Fig. 4 is a front elevation projected from Fig. 3. Fig. 5 is a sectional plan view of another improved clamp. Figs. 6 and 7 are end views thereof, illustrating its operation. Fig. 8 is a front view projected from Fig. 7. Fig. 9 is a top view of another improved clamp. Figs. 10 and 11 are end views thereof, illustrating its operation; and Fig. 12 is a front view projected from Fig. 11. 85

Like letters and numbers refer to like parts in all the figures.

The main body of the improved clamp in either species conveniently forms a link of a tentering-chain, as is customary, and comprises, preferably, a pair of rigid arms 1 and 2, to the free ends of which the movable upper jaw *a* of the clamp is pivoted by a horizontal rod 3. The other jaw *b* is in the form of or comprises the customary cloth-plate, 90 and a controller *c* or *c'* prevents the descent of the movable jaw into effective position until the selvage is drawn from beneath the controller, so that the selvage itself may be held between the jaws. Moreover, in all the spe- 95 100

cies a spring-pressure device comprising a spring or springs d or d^2 or d^3 is so applied as to permit a seam or the like to be accommodated between either end of the movable jaw and the cloth-plate without straining said arms or any other part of the clamp. In all the species, moreover, the movable jaw a is provided with the usual rigid lug 4, by which to open the clamp to receive the cloth, and a stop device, comprising a stop or stops 5 or 5', limits an appreciable travel of the movable jaw with the cloth, (represented by dotted lines at a in Figs. 3, 7, and 11,) as in said Winsor clamps. In the species represented by Figs. 1, 2, 3, and 4 the hinge-rod 3 forms, in connection with the coacting parts of the arms 1 and 2 and the movable jaw a , an ordinary hinge, such as is usually employed for the movable jaw of an adjustable clamp. The cloth-plate b is rendered vertically movable by a loose hinge-joint 6, attaching it at its rear edge to said body of the clamp in such manner as to permit either end of the cloth-plate to be raised or lowered relatively to the other end, as well as to permit the cloth-plate as a whole to move on the axis of said hinge-joint, and a pair of the springs d are arranged in sockets 7 beneath the respective ends of the cloth-plate, being supported beneath by screw-plugs 8, Fig. 2. The upward movement of the cloth-plate is limited by stops 9 at its ends, as best seen in Fig. 4. A pair of short spiral springs suffice in this arrangement, and the adjustment of the clamp is very easily effected by regulating the respective springs as to tension by means of the screw-plugs. The controller c in this as in any other form of the improved clamp may be of any known or improved construction adapted to permit said travel of the movable jaw a with the cloth. The specific device represented consists of a bar having a pivotal and sliding movement, being hinged to a projection 10 on the back of the movable jaw and sliding back and forth at its rear end on a rod 11, bridging the space between the arms 1 and 2 parallel with said hinge-rod 3 and occupying a longitudinal slot in the controller. The front end of the controller c rests at first upon the cloth, as in Fig. 2, above the customary slot 12 in the cloth-plate b , and when the selvage passes it, drops through the slot, as in Fig. 3, and permits the movable jaw a to bite the cloth. A pair of stops on one or each of the arms 1 and 2 and on the movable jaw a , respectively, constituting said stop device 5, limits the travel of the movable jaw a with the cloth, as aforesaid. Such travel is freely permitted by said slot in the controller c , and at its limit, when the stops at 5 come together, the cloth is held with the maximum power of the clamp, determined by the strength of the spring d . In the species represented by Figs. 5, 6, 7, and 8 the movable jaw a and the cloth-plate b are hinged as above described with reference to Figs. 1, 2, 3, and 4. The controller c is of the construction there shown, as before

described, and the travel of the movable jaw a with the cloth is limited by a pair of stops on one or each of the arms 1 and 2 and on the movable jaw a , respectively, constituting said stop device 5, as in the first species. In said second species a single spring d^2 , coiled in the manner represented in Fig. 8 and pressing horizontally against an abutment 13 at its middle and upwardly against the cloth-plate b at its respective extremities, takes the place of the pair of springs in the first species, with their appurtenances. A horizontal rod 14, held at its ends in those members of the stops 9 that are fast on the body of the clamp, supports the spring d^2 in effective position. In the species represented by Figs. 9, 10, 11, and 12 the rod 3, that hinges the movable jaw a , is mounted in a pair of boxes 15, slideable vertically in notches in the free ends of the arms 1 and 2, and two pairs of wire springs d^3 , rigidly attached to the sides of the arms 1 and 2, press downwardly on said boxes as the equivalent of the upwardly-pressing springs in the first and second species. It will be understood that in this arrangement the movable jaw a yields upwardly at either or both ends, and the cloth-plate b is rigidly supported beneath by the body of the clamp, as in Fig. 10 and 11. A different form of controller c' , which it projects rigidly from the jaw a , is shown in this species, and also a different form of stop device 5', the fixed member of which is supported by a bar 16, connecting the arms 1 and 2 near their free ends, and coacts with the lug 4, by which the movable jaw is operated to open the clamp, as above described.

Other forms and arrangements of the springs and stops, a pair of short pivots taking the place of either of the hinge-rods 3, and other like modifications will suggest themselves to those skilled in the art.

In the appended claims the term "arms" will be used to signify one or more arms performing the functions of the arms 1 and 2.

The term "vertically movable" is used to distinguish the movability of the hinge-rod 3 or its equivalent and the cloth-plate b from the pivotal movement of the jaw a .

Having thus described said improvement, I claim as my invention and desire to patent under this specification—

1. A cloth-clamp for textile machinery having, in combination with a pivotally-movable jaw, a hinge-rod therefor and a cloth-plate opposed to said jaw and hinge-rod, one of them vertically movable relatively to the other at either end of the clamp, and a spring device whereby such vertically-movable part is yieldingly supported in effective position; the clamping-space between the jaw and the cloth-plate being thus adapted to enlarge itself at either end of the clamp, for the accommodation of inequalities of the cloth.

2. A cloth-clamp for textile machinery having, in combination with a rigid body portion and with a pivotally-movable jaw, a horizon-

tal rod on which said jaw is hinged and a cloth-plate normally parallel with said rod, one of them vertically movable relatively to the other at either end of the clamp, and a 5 spring device whereby such vertically-movable part is yieldingly supported in normal position at its respective ends; the clamping-space between the jaw and the cloth-plate being thus adapted to enlarge itself at either 10 or both ends of the clamp without straining the rigid portions of the clamp.

3. A cloth-clamp for textile machinery having, in combination with a rigid body portion constructed with jaw-supporting arms and 15 with a pivotally-movable jaw hinged to said arms, a yielding cloth-support overhung by said arms, pressing upwardly against said movable jaw at the respective ends of the clamp; whereby the clamping-space between 20 said jaw and said cloth-support is adapted to enlarge itself at either or both ends without straining said arms.

4. A cloth-clamp, for textile machinery, having in combination a rigid body portion 25 constructed with jaw-supporting arms, a movable jaw hinged to said arms, a cloth-plate overhung by said arms and opposed to said movable jaw, a spring device supporting said cloth-plate in normal position and rendering 30 the same yielding, and stops limiting the return movements of said cloth-plate.

5. A cloth-clamp, for textile machinery, having in combination a rigid body portion constructed with jaw-supporting arms, a movable 35 jaw hinged to said arms, a cloth-plate overhung by said arms and opposed to said movable jaw, and a spring device supporting said cloth-plate in normal position and rendering the same yielding.

40 6. A cloth-clamp, for textile machinery, having in combination a rigid body portion constructed with jaw-supporting arms, a movable jaw, a horizontal rod by which said jaw is hinged to said arms, a cloth-plate overhung 45 by said arms and normally parallel with said rod, a loose hinge-joint connecting said cloth-plate with the body of the clamp and rendering it vertically movable at its respective ends, a spring device supporting said cloth-plate in normal position and rendering the 50 same yielding, and stops limiting the return movements of said cloth-plate.

7. A cloth-clamp, for textile machinery, having in combination a rigid body portion 55 constructed with jaw-supporting arms, a movable jaw, a horizontal rod by which said jaw is hinged to said arms, a cloth-plate overhung by said arms and normally parallel with said rod, a loose hinge-joint connecting said cloth-plate with the body of the clamp and rendering it vertically movable at its respective 60 ends, and a spring device supporting said cloth-plate in normal position and rendering the same yielding.

65 8. A cloth-clamp, for textile machinery, having in combination a rigid body portion, constructed with jaw-supporting arms, a mov-

able jaw, a horizontal rod by which said jaw is hinged to said arms, a cloth-plate overhung by said arms and normally parallel with said 70 rod, a hinge-rod, parallel with the rod first mentioned, on which said cloth-plate is movable, and a spring device whereby said cloth-plate is pressed against said movable jaw.

9. A cloth-clamp, for textile machinery, 75 having in combination a rigid body portion constructed with jaw-supporting arms, a movable jaw hinged to said arms, a cloth-plate overhung by said arms and having the customary controller-admitting slot, a controller 80 regulating the movement of said jaw into effective position and permitting a limited travel of the jaw with the cloth, a loose joint rendering said cloth-plate movable, and a spring device beneath the cloth-plate adapting 85 it to yield to inequalities in the cloth.

10. A cloth-clamp, for textile machinery, having in combination a rigid body portion constructed with jaw-supporting arms, a movable jaw hinged to said arms, a cloth-plate 90 hinged to the body portion and overhung by said arms, a controller regulating the movement of said jaw into effective position, means for stopping said jaw in such position, and a spring device pressing the cloth-plate against 95 the jaw in such effective position of the latter.

11. A cloth-clamp, for textile machinery, having in combination a rigid body portion constructed with jaw-supporting arms, a movable jaw hinged to said arms, a cloth-plate 100 overhung by said arms and loosely attached to said body portion, and springs beneath the respective ends of said cloth-plate rendering such respective ends yielding.

12. A cloth-clamp, for textile machinery, 105 having in combination a rigid body portion constructed with jaw-supporting arms, a movable jaw hinged to said arms, a cloth-plate overhung by said arms and loosely attached to said body portion, springs beneath the respective ends of said cloth-plate, rendering such respective ends yielding, and stops limiting the return movements of said cloth-plate.

13. A cloth-clamp, for textile machinery, 115 having in combination a rigid body portion constructed with jaw-supporting arms, a movable jaw hinged to said arms, a cloth-plate overhung by said arms and loosely attached to said body portion, springs beneath the respective ends of said cloth-plate rendering such respective ends yielding, and means for regulating said springs respectively as to tension.

14. A cloth-clamp, for textile machinery, 125 having in combination a rigid body portion constructed with jaw-supporting arms, a movable jaw hinged to said arms, a cloth-plate overhung by said arms and loosely hinged to said body portion, the axes of the hinges of 130 said jaw and plate being parallel with each other, springs beneath the respective ends of said cloth-plate whereby said plate is yieldingly pressed against said jaw, and means for

stopping said jaw and plate in normal position.

15. A cloth-clamp, for textile machinery, having in combination a body portion constructed with jaw-supporting arms, a movable jaw hinged to said arms, a cloth-plate loosely hinged to said body portion and provided with the customary controller-admitting slot, a controller limiting the movement of the jaw into effective position and slotted to permit the limited travel of the jaw with the cloth, stops for limiting such travel of the jaw, and

a spring device beneath the cloth-plate comprising a pair of short spiral springs beneath the respective ends of the cloth-plate, screw-plugs beneath the respective springs, rendering them adjustable as to tension, and stops limiting the upward movement of said cloth-plate.
